UNITED STATES PATENT OFFICE.

JOHN H. MORRIS, OF NORMAL, ILLINOIS.

IMPROVEMENT IN HARNESS-BUCKLES.

Specification forming part of Letters Patent No. 123,281, dated January 30, 1872.

Specification describing certain Improvements in Harness-Buckles, invented by JOHN H. MORRIS, of Normal, in the county of McLean and State of Illinois.

The invention will be first described in connection with all that is necessary to a full understanding thereof and then clearly pointed out in the claim.

Figure 1 is a longitudinal section, and Fig. 2 a plan view of my buckle.

A represents the frame, in which B is the upper and C the lower cross-bar, while D is the tongue. A' A'' are respectively the front and back ends of the frame. a is a recess in front A'. The tongue is pivoted to the front A' in recess a, and is bent downward therefrom at D' sufficiently to hold the strap in a plane below it, and then curved at d to rest conveniently on and about the cross-bar C.

The mode of operation is as follows: In or-

der to attach the strap, raise the heel of the buckle until the point of tongue enters a hole, and then draw the strap back. When it is necessary to remove the strap, pull or push it until the tongue leaves its hole, and then retract it.

Having thus described my invention, what I claim as new, and desire to secure by Letters Patent, is—

1. As an article of manufacture, a harness-buckle having frame A, cross-bars B C, and tongue D, constructed and relatively arranged as described.

2. The upper cross-bar B combined, as described, with tongue to hold the strap down to its horizontal position on the tongue.

JOHN H. MORRIS.
